UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

MINING MACHINE.

Application filed August 31, 1925. Serial No. 53,723.

This invention relates to mining machines and more particularly to mining machines of the continuous cutter type adapted to be fed laterally relative to the face of the coal to cut a substantially horizontal kerf thereunder.

An object of this invention is to provide an improved mining machine of the continuous cutter, room and pillar type having improved feeding means whereby the machine may be positioned relative to the face of the coal, moved about the mine, dumped into the coal, and fed laterally during its transverse cutting operation in an improved and more effective manner. Another object of my invention is the provision of improved feeding mechanism whereby the machine may be positioned, dumped, and fed laterally relative to the coal at different speeds and more particularly it is an object of the invention to provide improved feeding mechanism for such a machine wherein the feed operating member may be driven to draw in the flexible feeding member at three predetermined speeds, namely, a fast positioning speed, a slow cutting speed, and an intermediate dumping speed. A further object of the invention is to provide an improved mining machine having an improved arrangement of the mechanism for actuating the cutter chain and the feed operating members wherein, due to the location of the same, great compactness may be secured. Other objects of this invention will, however, subsequently appear.

In a preferred embodiment the invention may be embodied in a machine comprising a main frame slidable on its bottom or on a parallel opposite surface on the mine bottom and having carried thereby a projecting cutter chain carrying cutter bar. The machine may be propelled both during cutting and at other times preferably by a flexible feeding portion secured at its free end in advance of the advancing side of the machine while the angle of the machine relative to the face of the coal may be controlled by a second flexible portion secured at its free end at the rear of the receding side of the machine. A single motor preferably supplies power both to the cutting and feeding mechanisms and is mounted on the main frame at the forward end of the latter in a position overlying the rear end of the cutter bar. Power may be transmitted from

the motor to the cutting and feeding mechanisms by means including a pinion on the rear end of the armature shaft and an improved variable speed transmission mechanism. Preferably, the transmission mechanism comprises a plurality of coaxially arranged gearing units disposed on a transverse axis at the rear end of the machine frame and these are adapted to drive coaxially arranged feed operating and controlling drums at a plurality of speeds, thus permitting the machine to be positioned, dumped, and fed laterally relative to the face of the coal in an improved manner. These gearing units are preferably driven from the motor pinion through transmission means including a plurality of worms rotatable on parallel longitudinally extending axes and cooperating worm gears, rotation of the worms being under the control of manually operable friction clutch and brake devices.

In the accompanying drawings are shown for purposes of illustration one form and a modification which my invention may assume in practice.

In these drawings,—

Fig. 1 is a plan view of a mining machine constructed in accordance with an embodiment of my invention, the improved transmission means being shown in section.

Fig. 2 is a side elevational view of the machine shown in Fig. 1, a portion of the feeding and cutting transmission means being shown in central longitudinal vertical section.

Fig. 3 is a rear end elevational view of the machine shown in Figs. 1 and 2.

Fig. 4 is a transverse vertical sectional view taken substantially on line 4—4 of Fig. 1, parts of the mechanism being shown in elevation.

Fig. 5 is a detail transverse vertical sectional view taken substantially on line 5—5 of Fig. 1.

Fig. 6 is a slightly modified form of the portion of the transmission means shown in Figs. 1 and 2.

Referring to the drawings, 1 generally represents a mining machine of the continuous cutter room and pillar type having a frame 2 slidable on its bottom 3, or, at will, on its upper surface 3*, on the mine bottom and carrying a forwardly projecting rigid cutter bar 4 about the outer edges of which

a cutter bit carrying cutter chain 5 is adapted to be circulated in a usual manner. The frame 2 consists of a bed section 6, a motor section 7, and a feed section 8, the latter also housing a portion of the transmission means for actuating the cutter chain. As illustrated, the sections 7 and 8 are carried upon the bed section 6, the motor section 7 overlying the rear end of the cutter bar at 10 the forward end of the machine frame. The sections 7 and 8 are rigidly secured to the bed section in any approved manner. Disposed within the motor section 7 is a motor 9 which is herein preferably of the reversible electric type having a longitudinally extending horizontal armature shaft 10.

Referring specifically to the transmission means for actuating the cutter chain 5 it will herein be observed that secured as by 20 a key and screw connection 11 to the rear end of the armature shaft 10 is a spur motor pinion 12 having a reduced hub portion 13 journaled within suitable ball bearings 14 carried by a bracket 15 forming a portion 25 of the rear motor head. As illustrated, the motor pinion 12 meshes with a spur gear 16 splined as at 17 to a horizontal longitudinally extending transmission shaft 18 disposed below and extending rearwardly away 30 from the armature shaft 10. The shaft 18 is journaled in ball bearings 19, 20, and 21 suitably carried by the frame section 8. Moreover, splined as at 22 to the shaft 18 and disposed between the bearings 19 and 35 20 is a bevel pinion 23 which meshes with a large bevel gear 24 suitably journaled on a vertical axis within the bed section 6. Herein the bevel gear 24 is adapted to be connected in operative driving relation with a 40 vertically disposed shaft 25 by means of a reciprocable clutch member 26 splined as at 27 to the upper end of the shaft 25. Suitably secured to the lower end of the shaft 25 is a spur pinion 28 which meshes with a large 45 spur gear 29 secured in a suitable manner to a usual cutter chain driving sprocket 30 with which the cutter chain 5 cooperates. It will herein be noted that the clutch member 26 is adapted to be actuated by means 50 of a shipper member 31 (see Figs. 1 and 5) pivoted as at 32 on a portion of the frame section 8. As shown, the outer end of the shipper member 31 is connected by a link member 33 to an eccentric disk 34 suitably 55 secured to a longitudinally disposed actuating shaft 35 suitably journaled within the machine frame. The rear end of the shaft 35 is provided with a suitable operating member 36. It will thus be evident that by 60 suitable manipulation of the member 36 the eccentric disk 34 may be rotated, causing the shipper lever 31 to be swung about its pivot and the clutch member 26 reciprocated longitudinally of the shaft 25, thus permitting 65 the cutter chain sprocket to be actuated or

to remain idle at the will of the operator while the motor 9 continuously operates.

In specifically describing the improved feed transmission mechanism it will herein be noted that meshing with the spur gear 16 at opposite sides thereof are spur gears 37 and 38, respectively. These spur gears 37 and 38 are suitably secured to longitudinally extending horizontal drive shafts 39 and 40, respectively, disposed parallel with and at 70 opposite sides of the shaft 18 and these shafts are suitably journaled within bearings 41, 42 and 43 carried by the machine frame. Furthermore, it will be noted that disposed coaxially with and journaled on the shafts 18, 39 and 40, respectively, are worms 44, 45 and 46. These worms are of the non-self-locking type. The rotation of these worms is adapted to be controlled by combined clutch and brake devices to be hereinafter described. 80 As shown, the central worm 44 is meshed with a worm gear 47 disposed on a horizontal transverse axis and splined as at 48 to the adjacent hubs of coaxially arranged bevel gears 49 and 50, the latter gears meshing with beveled planetary pinions 51 and 52, respectively. As illustrated, the planetary gears 51 and 52 are journaled upon radially disposed shafts 53 supported by suitable carrier members 54 splined as at 55 to 90 coaxially arranged transmission shafts 56 and 57, respectively, disposed coaxially with the bevel gears 49 and 50. Arranged at each side of and supporting the hub of the worm gear 47 are suitable ball bearings 58 thus forming a stable support for the gear and shafts. Furthermore, the inner adjacent ends of the shafts 56 and 57 are journaled within a bearing sleeve 59 disposed within the hubs of the bevel gears 49 and 50 while the outer ends of these shafts are journaled in ball bearings 62 suitably carried by the machine frame 2. Meshing with the worms 45 and 46, respectively, are worm gears 63 and 64 splined as at 65 to the hubs of bevel gears 66 and 67, respectively, the latter being arranged coaxially with the bevel gears 49 and 50. The gears 66 and 67 also mesh with the planetary pinions 51 and 52, respectively. Splined as at 68 to the outer ends 100 of the shafts 56 and 57, respectively, are feed operating members 69 and 70, herein in the form of drums, adapted to wind in or pay out flexible feeding members or cables 71 and 72, the former forming the advance 110 feeding member while the latter forms the receding feeding and controlling member. Carried by the forward end of the machine frame are guide sheaves 71^a while disposed at the rear end of the machine frame are 120 suitable guide sheaves 72^a and these sheaves are adapted to guide the cables 71 and 72 in a suitable manner during the various operations of the machine.

The combined clutch and brake devices for 130

controlling rotation of the worms 44, 45 and 46 are generally designated 73, 74 and 75 and as they are of substantially the same structure the description of one will suffice for all. 5 As shown, splined to the rear end of the shaft 18 is a clutch member 76 carrying a series of clutch disks 77 which are interleaved with a series of clutch disks 78 carried by a clutch housing member 79 splined as at 80 to 10 a sleeve portion 81 formed on the worm 44. As shown, keyed to the sleeve 81 in advance of the member 76 is a member 82 which carries a series of clutch disks 83 which are interleaved with a series of clutch disks 84 carried by a housing member 85 secured as at 15 86 to the machine frame 2. Interposed between the housing 85 and the housing 79 is a clutch applying member 87 having projecting fingers 88 and 89 engaging certain of the 20 series of clutch disks 83, 84 and 77, 78, respectively. Cooperating with the clutch applying member 87 is a reciprocable shipper 90 adapted to be actuated by means of a handle 91 suitably carried at the rear end of 25 the machine frame. From the foregoing it will be evident that when the clutches 77, 78 of the devices 73, 74 and 75 are applied, the worms 44, 45, and 46 may be driven by the shafts 18, 39 and 40, respectively. Furthermore, it will be evident that when the clutches 30 77, 78 are released and the clutches 83, 84 are applied, rotation of the worms 44, 45 and 46 is prevented, the clutch disks connecting the worm sleeves 81 with the stationary housing members 85.

In the modified form of structure shown in Fig. 6 in which corresponding parts bear similar reference characters, but with "a" appended, it will be noted that improved means 40 are provided for driving the central worm 44 at different predetermined speeds in the same direction and such means comprises a spur pinion 92 disposed coaxially with the spur gear 37^a and suitably secured to the shaft 39^a and this pinion 92 meshes with a spur gear 93 loosely journaled on the shaft 18^a. Furthermore, the gear 16^a is also loosely journaled on the shaft 18^a instead of being splined thereto as in the form of my 45 invention shown in Fig. 2. Gear 23, not shown, is rotatable with gear 16^a. Interposed between the gears 16^a and 93 and splined as at 94 to the shaft 18^a is a jaw clutch member 95 having oppositely disposed 50 clutch teeth 96 and 97 adapted to engage clutch teeth 98 and 99 formed on the gears 16^a and 93, respectively. A suitable shipper mechanism 100 having any conveniently located and actuated control member is provided for actuating the clutch member 95. From the foregoing it will be evident that when the gear 16^a is connected by the clutch 55 95 to the transmission shaft 18, the worm 44, when the friction clutch 77, 78 is connected, may be driven at a fast speed, while if the

gear 93 is connected to the transmission shaft 18^a and the gear 16^a disconnected, the worm 44 may be driven through the gears 12, 16^a, 37^a, 92 and 93 at a relatively slower speed in the same direction. 70

In the operation of the first form of my improved mining machine it will be noted that when the machine is unloaded from its transport truck one or the other of the cables 71, 72 may be extended to a point adjacent the right hand rib and anchored in position as by a suitable roof jack or take up device. During this positioning operation the maximum machine moving speed may advantageously be used and accordingly by connecting both the worm 44 and whichever one of the worms 45, 46 is to be used to their shafts through the manipulation of the clutch 73 and the clutch 74 or 75, a maximum winding speed may be obtained, since, for example, the gears 50 and 67 will simultaneously rotate in the same direction and so the speed of rotation imparted to the shaft 57 will be the sum of the effects of rotation of the gears 50 and 67. When the machine has 90 been moved to the position in which sumping is to be begun, the controlling cable 72 is anchored in the desired position at the right hand rib while the feed cable 71 is extended from the drum 69 around the front guide sheave 71^a and laterally to the left hand rib of the coal adjacent the face in a well known manner. The clutch 77 and 78 of the device 73 controlling rotation of the worm 44 is then applied causing the latter to drive the worm gear 47 and the bevel gears 49 and 50, the clutches effecting rotation of the worms 45, 46 being released at this time and the worm 46 held stationary by loading of the clutch 83, 84 associated therewith, while the worm 45 is permitted to slip backwards under the control of its corresponding partially loaded clutch disks at a sufficient rate to maintain the length of the cable 71 constant. During the winding operation shortening 100 the flexible portion 72 the pinions 52 are rolled around upon the then stationary gear 67 and the parts are proportioned and designed to provide the desired sumping speed. When cutting across the face is to commence, 110 the clutch disks 77, 78 of the device 74 are loaded, the clutch disks 83 and 84 of the device 73 loaded, and the disks 83 and 84 of the device 75 partially loaded. As a result the planet gears 51 are driven by the gear 66 about the reaction gear 49 which is then stationary and by reason of the slower speed of rotation of the gear 66 secured by the reduction between the elements 16 and 37 and by suitable design of the teeth of the worm 45, 120 the cable 71 is caused to be wound in at a cutting speed. The cable 72 is permitted to pay out against the resistance opposed to turning of the worm 46 by the loading of the clutch disks 83 and 84 which serve to con- 130

nect it in adjustable slipping relation to a stationary part of the machine frame. From what has been said the method of angling the machine will be clear to any one skilled in the art and also the manner in which any other operations which may be desired can be accomplished will also be plain.

Referring now more particularly to the modified construction, it will be evident that with the worm 44^a of substantially steeper pitch in view of the reduction effected by drive through the pinion 16^a, gear 37^a, pinion 92 and gear 93, which transmission is employed when a sumping speed is desired, a much higher speed may be secured for machine moving, since when the worm 44^a is driven directly from the gear 16^a the sum of the speeds transmitted to the bevel pinions will naturally be largely augmented. Further description of the mode of operation of this form of the invention is believed unnecessary as in general with the exception of the provision of this additional higher machine moving speed the arrangement and operation correspond closely to that of the first species.

As a result of this invention it will be noted that a mining machine is provided having improved feeding mechanism whereby the machine may be moved about the mine at one speed, sumped into the coal at a slower speed, and fed transversely relative to the face at a slow or cutting speed. It will be observed further in view of the possible modifications of the gearing that particularly in the second form or modification described an extremely desirable combination of speeds can be obtained, for the cutting speed may be slow, the sumping speed somewhat higher, perhaps two or three times the cutting speed, and the machine moving speed may be made as large or as small as is desired.

While I have in this application specifically described two forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements and rotatable thereby, worms operatively connected to said coaxial elements, and

means for effecting rotation of said member on orbital movement of said planet means.

2. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, horizontal worms operatively connected to said coaxial elements, and means for effecting rotation of said member on orbital movement of said planet means. 80

3. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms rotating on axes in longitudinally extending vertical planes operatively connected to said coaxial elements respectively, and means for effecting rotation of said member on orbital movement of said planet means. 90

4. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms rotating on axes lying in the same transversely extending plane operatively connected to said coaxial elements respectively, and means for effecting rotation of said member on orbital movement of said planet means. 100

5. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, horizontal worms rotating on axes lying in the same transversely extending plane operatively connected to said coaxial elements, and means for effecting rotation of said member on orbital movement of said planet means. 110

6. In a mining machine, a motor, and feeding mechanism operated by said motor including a flexible feeding portion, a rotatable feed operating and controlling member cooperating directly therewith, and operating and controlling means for said mem- 120
125
130

ber including coaxial elements rotating on transversely extending horizontal axes, planet means cooperating with said elements, worms operatively connected to said 5 coaxial elements, means for rotating either or both of said worms, and means for effecting rotation of said member on orbital movement of said planet means.

19 7. In a mining machine, a motor, and
feeding mechanism operated by said motor
including a flexible feeding portion, a rotat-
able feed operating and controlling member
cooperating directly therewith, and operat-
ing and controlling means for said member
including coaxial elements rotating on trans-
versely extending horizontal axes, planet
means cooperating with said elements, hori-
zontal worms operatively connected to said
coaxial elements, means for rotating either
or both of said worms, and means for ef-
fecting rotation of said member on orbital
movement of said planet means.

8. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms rotating on axes in longitudinally extending vertical planes operatively connected to said coaxial elements, means for rotating either or both of said worms, and means for effecting rotation of said member on orbital movement of said planet means.

9. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms operatively connected to said coaxial elements, means for rotating either of said worms while the other is stationary, and means for effecting rotation of said member on orbital movement of said planet means.

10. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, horizontal worms operatively connected to said coaxial elements, means for rotating either of said worms while the other is stationary, and means for effecting rotation of

said member on orbital movement of said planet means.

11. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms rotating on axes in longitudinally extending vertical planes operatively connected to said coaxial elements, means for rotating either of said worms while the other is stationary, and means for effecting rotation of said member on orbital movement of said planet means. 70 75 80

12. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms operatively connected to said coaxial elements, means for rotating either of said worms while the other is stationary, and means for effecting rotation of said member on orbital movement of said planet means. 85 90 95

13. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, horizontal worms operatively connected to said coaxial elements, means for rotating either of said worms while the other is stationary, and means for effecting rotation of said member on orbital movement of said planet means. 100 105 110

14. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms rotating on axes in longitudinally extending vertical planes operatively connected to said coaxial elements, means for rotating either of said worms while the other is stationary, and means for effecting rotation of said member on orbital movement of said planet means. 120 125 115

15. In a mining machine, a motor, and 130

24. In a mining machine, a motor, and feeding mechanism operated by said motor including a flexible feeding portion, a rotatable feed operating and controlling member cooperating directly therewith, and operating and controlling means for said member including like coaxial elements rotating on transversely extending horizontal axes, planet means cooperating with said elements, horizontal worms operatively connected to said coaxial elements, means for rotating either of said worms while the other is stationary, and means for effecting rotation of said member on orbital movement of said planet means.

25. In a mining machine, a motor, and feeding mechanism operated by said motor including a flexible feeding portion, a rotatable feed operating and controlling member cooperating directly therewith, and operating and controlling means for said member including like coaxial elements rotating on transversely extending horizontal axes, planet means cooperating with said elements, worms rotating on axes in longitudinally extending vertical planes operatively connected to said coaxial elements, means for rotating either of said worms while the other is stationary, and means for effecting rotation of said member on orbital movement of said planet means.

26. In a mining machine, a motor, and feeding mechanism operated by said motor including a flexible feeding portion, a rotatable feed operating and controlling member cooperating directly therewith, and operating and controlling means for said member including like coaxial elements rotating on transversely extending horizontal axes, planet means cooperating with said elements, worms operatively connected to said coaxial elements, means for rotating either of said worms continuously while the other is stationary, and means for effecting rotation of said member on orbital movement of said planet means.

27. In a mining machine, a motor, and feeding mechanism operated by said motor including a flexible feeding portion, a rotatable feed operating and controlling member cooperating directly therewith, and operating and controlling means for said member including like coaxial elements rotating on transversely extending horizontal axes, planet means cooperating with said elements, horizontal worms operatively connected to said coaxial elements, means for rotating either of said worms continuously while the other is stationary, and means for effecting rotation of said member on orbital movement of said planet means.

28. In a mining machine, a motor, and feeding mechanism operated by said motor including a flexible feeding portion, a rotatable feed operating and controlling mem-

ber cooperating directly therewith, and operating and controlling means for said member including like coaxial elements rotating on transversely extending horizontal axes, planet means cooperating with said elements, worms rotating on axes in longitudinally extending vertical planes operatively connected to said coaxial elements, means for rotating either of said worms continuously while the other is stationary, and means for effecting rotation of said member on orbital movement of said planet means.

29. In a mining machine, feeding mechanism including a plurality of pairs of coaxial elements rotating on horizontal transversely extending axes, planet means cooperating with the elements of each pair, means for rotating said coaxial elements including worms rotating on axes arranged in longitudinally extending vertical planes, one of said worms driving an element of each pair, and separate feed operating members each adapted to cooperate directly with flexible feeding means and each driven and controlled through one of said pairs of coaxial elements.

30. In a mining machine, feeding mechanism including a plurality of pairs of coaxial elements rotating on horizontal transversely extending axes, planet means cooperating with the elements of each pair, means for rotating said coaxial elements including worms rotating on horizontal axes, one of said worms driving an element of each pair, and separate feed operating members each adapted to cooperate directly with flexible feeding means and each driven and controlled through one of said pairs of coaxial elements.

31. In a mining machine, feeding mechanism including a plurality of pairs of coaxial elements rotating on horizontal transversely extending axes, planet means cooperating with the elements of each pair, means for rotating said coaxial elements including worms rotating on axes arranged in longitudinally extending vertical planes lying in the same transverse plane, one of said worms driving an element of each pair, and separate feed operating members each adapted to cooperate directly with flexible feeding means and each driven and controlled through one of said pairs of coaxial elements.

32. In a mining machine, feeding mechanism including a plurality of pairs of coaxial elements rotating on horizontal transversely extending axes, planet means cooperating with the elements of each pair, means for rotating said coaxial elements including worms rotating on horizontal axes lying in the same transverse plane, one of said worms driving an element of each pair, separate feed operating members each adapted to cooperate directly with flexible

feeding means and each driven and controlled through one of said pairs of coaxial elements, and means for effecting rotation of said members on orbital movement of said planet means.

33. In a mining machine, feeding mechanisms including a plurality of pairs of coaxial elements rotating on horizontal transversely extending axes, planet means cooperating with the elements of each pair, and means for rotating said coaxial elements including three worms rotating on axes arranged in longitudinally extending vertical planes, the central worm driving an element of each pair, and means for effecting rotation of said worms including means for rotating said last mentioned worm at different speeds.

34. In a mining machine, feeding mechanisms including a plurality of pairs of coaxial elements rotating on horizontal transversely extending axes, planet means cooperating with the elements of each pair, and means for rotating said coaxial elements including three worms rotating on horizontal axes, the central worm driving an element of each pair, and means for effecting rotation of said worms including means for rotating said last mentioned worm at different speeds.

35. In a mining machine, feeding mechanism including a plurality of pairs of coaxial elements rotating on horizontal transversely extending axes, planet means cooperating with the elements of each pair, and means for rotating said coaxial elements including three worms rotating on axes arranged in longitudinally extending vertical planes, the central worm driving an element of each pair, and means for effecting rotation of said worms including means for rotating said last mentioned worm at different speeds or allowing it to remain stationary.

36. In a mining machine, feeding mechanism including a plurality of pairs of coaxial elements rotating on horizontal transversely extending axes, planet means cooperating with the elements of each pair, and means for rotating said coaxial elements including three worms rotating on horizontal axes, the central worm driving an element of each pair, and means for effecting rotation of said worms including means for rotating said last mentioned worm at different speeds or allowing it to remain stationary.

37. In a mining machine, feeding mechanism including a plurality of pairs of coaxial elements rotating on horizontal transversely extending axes, planet means cooperating with the elements of each pair, and means for rotating said coaxial elements including three worms rotating on axes arranged in longitudinally extending vertical planes, the central worm driving an element of each pair, and means for effecting rotation of said worms including means for ro-

tating said last mentioned worm at different speeds and said other worms at like speeds in the same direction.

38. In a mining machine, feeding mechanism including a plurality of pairs of coaxial elements rotating on horizontal transversely extending axes, planet means cooperating with the elements of each pair, and means for rotating said coaxial elements including three worms rotating on horizontal axes, the central worm driving an element of each pair, and means for effecting rotation of said worms including means for rotating said last mentioned worm at different speeds and said other worms at like speeds in the same direction.

39. In a mining machine, feeding mechanism including a plurality of pairs of coaxial elements rotating on horizontal transversely extending axes, planet means cooperating with the elements of each pair, and means for rotating said coaxial elements including three worms rotating on axes arranged in longitudinally extending vertical planes, the central worm driving an element of each pair, and means for effecting rotation of said worms including means for rotating said last mentioned worm at different speeds or allowing it to remain stationary and said other worms at like speeds in the same direction.

40. In a mining machine, feeding mechanism including a plurality of pairs of coaxial elements rotating on horizontal transversely extending axes, planet means cooperating with the elements of each pair, and means for rotating said coaxial elements including three worms rotating on horizontal axes, the central worm driving an element of each pair, and means for effecting rotation of said worms including means for rotating said last mentioned worm at different speeds or allowing it to remain stationary and said other worms at like speeds in the same direction.

41. In a mining machine, feeding mechanism including a plurality of pairs of like coaxial elements rotating on horizontal transversely extending axes, planet means cooperating with the elements of each pair, means for rotating said coaxial elements including a plurality of worms one of which drives an element of each pair, and separate feed operating members each adapted to cooperate directly with flexible feeding means and each driven and controlled through one of said pairs of coaxial elements.

42. In a mining machine, feeding mechanism including a plurality of pairs of like coaxial elements rotating on horizontal transversely extending axes, planet means cooperating with the elements of each pair, means for rotating said coaxial elements including a plurality of worms rotating on parallel axes, one of which drives an ele-

ment of each pair, and separate feed operating members each adapted to cooperate directly with flexible feeding means and each driven and controlled through one of said 5 pairs of coaxial elements.

43. In a mining machine, feeding mechanism including a plurality of pairs of like coaxial elements rotating on horizontal transversely extending axes, planet means 10 cooperating with the elements of each pair, means for rotating said coaxial elements including a plurality of worms rotating on horizontal axes, one of which drives an element of each pair, and separate feed operating members each adapted to cooperate directly with flexible feeding means and each driven and controlled through one of 15 said pairs of coaxial elements.

44. In a mining machine, feeding mechanism including a plurality of pairs of like coaxial elements rotating on horizontal transversely extending axes, planet means cooperating with the elements of each pair, means for rotating said coaxial elements including a plurality of worms rotating on axes lying in parallel planes extending longitudinally of the machine, one of which drives an element of each pair, and separate feed operating members each adapted to cooperate directly with flexible feeding means and each driven and controlled through one of 25 said pairs of coaxial elements.

45. In a mining machine, feeding mechanism including a plurality of pairs of like coaxial elements rotating on horizontal transversely extending axes, planet means cooperating with the elements of each pair, means for rotating said coaxial elements including a plurality of worms rotating on axes lying in 30 the same transverse plane, one of which drives an element of each pair, and separate feed operating members each adapted to cooperate directly with flexible feeding means and each driven and controlled through one of 35 said pairs of coaxial elements.

46. In a mining machine, feeding mechanism including a plurality of pairs of like coaxial elements rotating on horizontal transversely extending axes, planet means 40 cooperating with the elements of each pair, means for rotating said coaxial elements including three worms, the central worm driving an element of each pair, and separate feed operating members each adapted to cooperate directly with flexible feeding means and each driven and controlled through one of 45 said pairs of coaxial elements.

47. In a mining machine, feeding mechanism including a plurality of pairs of like coaxial elements rotating on horizontal transversely extending axes, planet means 50 cooperating with the elements of each pair, means for rotating said coaxial elements including three worms rotating on parallel axes, the central worm driving an element 55

of each pair, and separate feed operating members each adapted to cooperate directly with flexible feeding means and each driven and controlled through one of said pairs of coaxial elements.

48. In a mining machine, feeding mechanism including a plurality of pairs of like coaxial elements rotating on horizontal transversely extending axes, planet means 70 cooperating with the elements of each pair, means for rotating said coaxial elements including three worms rotating on horizontal axes, the central worm driving an element of each pair, and separate feed operating members each adapted to cooperate directly with flexible feeding means and each driven and controlled through one of said pairs of coaxial elements.

49. In a mining machine, feeding mechanism including a plurality of pairs of like coaxial elements rotating on horizontal transversely extending axes, planet means 75 cooperating with the elements of each pair, means for rotating said coaxial elements including three worms rotating on axes lying in parallel planes extending longitudinally of the machine, the central worm driving an element of each pair, and separate feed operating members each adapted to cooperate directly with flexible feeding means and each driven and controlled through one of 80 said pairs of coaxial elements.

50. In a mining machine, feeding mechanism including a plurality of pairs of like coaxial elements rotating on horizontal transversely extending axes, planet means 85 cooperating with the elements of each pair, means for rotating said coaxial elements including three worms rotating on axes lying in the same transverse plane, the central worm driving an element of each pair, and separate feed operating members each adapted to cooperate directly with flexible feeding means and each driven and controlled through one of 90 said pairs of coaxial elements.

51. In a mining machine, feeding mechanism including a plurality of pairs of like coaxial elements rotating on horizontal transversely extending axes, planet means 100 cooperating with the elements of each pair, means for rotating said coaxial elements including three worms rotating on axes lying in the same transverse plane, the central worm driving an element of each pair, and separate feed operating members each adapted to cooperate directly with flexible feeding means and each driven and controlled through one of 105 said pairs of coaxial elements.

52. In a mining machine, feeding mechanism including a plurality of pairs of like coaxial elements rotating on horizontal transversely extending axes, planet means 110 cooperating with the elements of each pair, means for rotating said coaxial elements including a plurality of worms one of which drives an element of each pair, and means to effect rotation of said worms including 115 means for rotating each of said worms at will or holding it against rotation, and separate feed operating members each adapted to cooperate directly with flexible feeding means and each driven and controlled through one of 120 said pairs of coaxial elements.

53. In a mining machine, feeding mechanism including a plurality of pairs of like coaxial elements rotating on horizontal transversely extending axes, planet means 125

transversely extending axes, planet means cooperating with the elements of each pair, means for rotating said coaxial elements including a plurality of worms rotating on parallel axes, one of which drives an element of each pair, and means to effect rotation of said worms including means for rotating each of said worms at will or holding it against rotation, and separate feed operating members each adapted to cooperate directly with flexible feeding means and each driven and controlled through one of said pairs of coaxial elements.

53. In a mining machine, feeding mechanism including a plurality of pairs of like coaxial elements rotating on horizontal transversely extending axes, planet means cooperating with the elements of each pair, means for rotating said coaxial elements including a plurality of worms rotating on horizontal axes, one of which drives an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

54. In a mining machine, feeding mechanism including a plurality of pairs of like coaxial elements rotating on horizontal transversely extending axes, planet means cooperating with the elements of each pair, means for rotating said coaxial elements including a plurality of worms rotating on axes lying in parallel planes extending longitudinally of the machine, one of which drives an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

55. In a mining machine, feeding mechanism including a plurality of pairs of like coaxial elements rotating on horizontal transversely extending axes, planet means cooperating with the elements of each pair, means for rotating said coaxial elements including a plurality of worms rotating on axes lying in the same transverse plane, one of which drives an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

56. In a mining machine, feeding mecha-

nism including a plurality of pairs of like coaxial elements rotating on horizontal transversely extending axes, planet means cooperating with the elements of each pair, means for rotating said coaxial elements including three worms, the central worm driving an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

57. In a mining machine, feeding mechanism including a plurality of pairs of like coaxial elements rotating on horizontal transversely extending axes, planet means cooperating with the elements of each pair, means for rotating said coaxial elements including three worms rotating on parallel axes, the central worm driving an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

58. In a mining machine, feeding mechanism including a plurality of pairs of like coaxial elements rotating on horizontal transversely extending axes, planet means cooperating with the elements of each pair, means for rotating said coaxial elements including three worms rotating on horizontal axes, the central worm driving an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

59. In a mining machine, feeding mechanism including a plurality of pairs of like coaxial elements rotating on horizontal transversely extending axes, planet means cooperating with the elements of each pair, means for rotating said coaxial elements including three worms rotating on axes lying in parallel planes extending longitudinally of the machine, the central worm driving an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

60. In a mining machine, feeding mechanism including a plurality of pairs of like

coaxial elements rotating on horizontal transversely extending axes, planet means cooperating with the elements of each pair, means for rotating said coaxial elements including three worms rotating on axes lying in the same transverse plane, the central worm driving an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

61. In a mining machine, feeding mechanism including a plurality of pairs of like coaxial elements rotating on horizontal transversely extending axes, planet means cooperating with the elements of each pair, and means for rotating said coaxial elements including a plurality of worms one of which drives an element of each pair, and means for rotating each of said worms at will including means for rotating one of said worms at a plurality of speeds and means for holding each of said worms stationary.

62. In a mining machine, feeding mechanism including a plurality of pairs of like coaxial elements rotating on horizontal transversely extending axes, planet means cooperating with the elements of each pair, and means for rotating said coaxial elements including a plurality of worms rotating on parallel axes, one of which drives an element of each pair, and means for rotating each of said worms at will including means for rotating one of said worms at a plurality of speeds and means for holding each of said worms stationary.

63. In a mining machine, feeding mechanism including a plurality of pairs of like coaxial elements rotating on horizontal transversely extending axes, planet means cooperating with the elements of each pair, and means for rotating said coaxial elements including a plurality of worms rotating on horizontal axes, one of which drives an element of each pair, and means for rotating each of said worms at will including means for rotating one of said worms at a plurality of speeds and means for holding each of said worms stationary.

64. In a mining machine, feeding mechanism including a plurality of pairs of like coaxial elements rotating on horizontal transversely extending axes, planet means cooperating with the elements of each pair, and means for rotating said coaxial elements including a plurality of worms rotating on axes lying in parallel planes extending longitudinally of the machine, one of which drives an element of each pair, and means for rotating each of said worms at will in-

cluding means for rotating one of said worms at a plurality of speeds and means for holding each of said worms stationary.

65. In a mining machine, feeding mechanism including a plurality of pairs of like coaxial elements rotating on horizontal transversely extending axes, planet means cooperating with the element of each pair, and means for rotating said coaxial elements including a plurality of worms rotating on axes lying in the same transverse plane, one of which drives an element of each pair, and means for rotating each of said worms at will including means for rotating one of said worms at a plurality of speeds and means for holding each of said worms stationary.

66. In a mining machine, feeding mechanism including a plurality of pairs of like coaxial elements rotating on horizontal transversely extending axes, planet means cooperating with the element of each pair, and means for rotating said coaxial elements including three worms, the central worm driving an element of each pair, and means for rotating each of said worms at will including means for rotating one of said worms at a plurality of speeds and means for holding each of said worms stationary.

67. In a mining machine, feeding mechanism including a plurality of pairs of like coaxial elements rotating on horizontal transversely extending axes, planet means cooperating with the elements of each pair, and means for rotating said coaxial elements including three worms rotating on parallel axes, the central worm driving an element of each pair, and means for rotating each of said worms at will including means for rotating one of said worms at a plurality of speeds and means for holding each of said worms stationary.

68. In a mining machine, feeding mechanism including a plurality of pairs of like coaxial elements rotating on horizontal transversely extending axes, planet means cooperating with the elements of each pair, and means for rotating said coaxial elements including three worms rotating on horizontal axes, the central worm driving an element of each pair, and means for rotating each of said worms at will including means for rotating one of said worms at a plurality of speeds and means for holding each of said worms stationary.

69. In a mining machine, feeding mechanism including a plurality of pairs of like coaxial elements rotating on horizontal transversely extending axes, planet means cooperating with the elements of each pair, and means for rotating said coaxial elements including three worms rotating on axes lying in parallel planes extending longitudinally of the machine, the central worm driving an element of each pair, and means for

rotating each of said worms at will including means for rotating one of said worms at a plurality of speeds and means for holding each of said worms stationary.

- 5 70. In a mining machine, feeding mechanism including a plurality of pairs of like coaxial elements rotating on horizontal transversely extending axes, planet means cooperating with the elements of each pair, 75
10 and means for rotating said coaxial elements including three worms rotating on axes lying in the same transverse plane, the central worm driving an element of each pair, and means for rotating each of said worms at 15 will including means for rotating one of said worms at a plurality of speeds and means for holding each of said worms stationary.

71. In a mining machine, feeding mechanism including a plurality of pairs of like coaxial elements rotating on horizontal transversely extending axes, planet means cooperating with the elements of each pair, and means for rotating said coaxial elements including three worms, the central worm 20 driving an element of each pair, and means for rotating each of said worms at will including means for rotating said central worm at a plurality of speeds and means for holding each of said worms stationary.

- 25 72. In a mining machine, feeding mechanism including a plurality of pairs of like coaxial elements rotating on horizontal transversely extending axes, planet means cooperating with the elements of each pair, 30 and means for rotating said coaxial elements including three worms rotating on parallel axes, the central worm driving an element of each pair, and means for rotating each of said worms at will including means for 35 rotating said central worm at a plurality of speeds and means for holding each of said worms stationary.

- 40 73. In a mining machine, feeding mechanism including a plurality of pairs of like coaxial elements rotating on horizontal transversely extending axes, planet means cooperating with the elements of each pair, and means for rotating said coaxial elements including three worms rotating on horizontal 45 axes, the central worm driving an element of each pair, and means for rotating each of said worms at will including means for rotating said central worm at a plurality of speeds and means for holding each of said worms stationary.

- 45 74. In a mining machine, feeding mechanism including a plurality of pairs of like coaxial elements rotating on horizontal transversely extending axes, planet means 50 cooperating with the elements of each pair, and means for rotating said coaxial elements including three worms rotating on axes lying in parallel planes extending longitudinally of the machine, the central worm 55 driving an element of each pair, and means

for rotating each of said worms at will including means for rotating said central worm at a plurality of speeds and means for holding each of said worms stationary.

75. In a mining machine, feeding mechanism including a plurality of pairs of like coaxial elements rotating on horizontal transversely extending axes, planet means cooperating with the elements of each pair, and means for rotating said coaxial elements including three worms rotating on axes lying in the same transverse plane, the central worm driving an element of each pair, and means for rotating each of said worms at will including means for rotating said central worm at a plurality of speeds and means for holding each of said worms stationary. 75
80

76. In a mining machine, feeding mechanism including a plurality of coaxial pairs of like coaxial elements rotating on horizontal transversely extending axes, planet means cooperating with the elements of each pair, means for rotating said coaxial elements including a plurality of worms one of which drives an element of each pair, and separate feed operating members each adapted to cooperate directly with flexible feeding means and each driven and controlled through one of said pairs of coaxial elements. 85
90

77. In a mining machine, feeding mechanism including a plurality of coaxial pairs of like coaxial elements rotating on horizontal transversely extending axes, planet means cooperating with the elements of each pair, means for rotating said coaxial elements including a plurality of worms rotating on parallel axes, one of which drives an element of each pair, and separate feed operating members each adapted to cooperate directly with flexible feeding means and each driven and controlled through one of said pairs of coaxial elements. 95
100

78. In a mining machine, feeding mechanism including a plurality of coaxial pairs of like coaxial elements rotating on horizontal transversely extending axes, planet means cooperating with the elements of each pair, means for rotating said coaxial elements including a plurality of worms rotating on horizontal axes, one of which drives an element of each pair, and separate feed operating members each adapted to cooperate directly with flexible feeding means and each driven and controlled through one of said pairs of coaxial elements. 110
115

79. In a mining machine, feeding mechanism including a plurality of coaxial pairs of like coaxial elements rotating on horizontal transversely extending axes, planet means cooperating with the elements of each pair, means for rotating said coaxial elements including a plurality of worms rotating on axes lying in parallel planes extending longitudinally of the machine, one of which drives an element of each pair, and separate 120
125

130

- feed operating members each adapted to cooperate directly with flexible feeding means and each driven and controlled through one of said pairs of coaxial elements.
80. In a mining machine, feeding mechanism including a plurality of coaxial pairs of like coaxial elements rotating on horizontal transversely extending axes, planet means cooperating with the elements of each pair, means for rotating said coaxial elements including a plurality of worms rotating on axes lying in the same transverse plane, one of which drives an element of each pair, and separate feed operating members each adapted to cooperate directly with flexible feeding means and each driven and controlled through one of said pairs of coaxial elements.
81. In a mining machine, feeding mechanism including a plurality of coaxial pairs of like coaxial elements rotating on horizontal transversely extending axes, planet means cooperating with the elements of each pair, means for rotating said coaxial elements including three worms, the central worm driving an element of each pair, and separate feed operating members each adapted to cooperate directly with flexible feeding means and each driven and controlled through one of said pairs of coaxial elements.
82. In a mining machine, feeding mechanism including a plurality of coaxial pairs of like coaxial elements rotating on horizontal transversely extending axes, planet means cooperating with the elements of each pair, means for rotating said coaxial elements including three worms rotating on parallel axes, the central worm driving an element of each pair, and separate feed operating members each adapted to cooperate directly with flexible feeding means and each driven and controlled through one of said pairs of coaxial elements.
83. In a mining machine, feeding mechanism including a plurality of coaxial pairs of like coaxial elements rotating on horizontal transversely extending axes, planet means cooperating with the elements of each pair, means for rotating said coaxial elements including three worms rotating on horizontal axes, the central worm driving an element of each pair, and separate feed operating members each adapted to cooperate directly with flexible feeding means and each driven and controlled through one of said pairs of coaxial elements.
84. In a mining machine, feeding mechanism including a plurality of coaxial pairs of like coaxial elements rotating on horizontal transversely extending axes, planet means cooperating with the elements of each pair, means for rotating said coaxial elements including three worms rotating on axes lying in parallel planes extending longitudinally of the machine, the central worm driving an element of each pair, and separate feed operating members each adapted to cooperate directly with flexible feeding means and each driven and controlled through one of said pairs of coaxial elements.
85. In a mining machine, feeding mechanism including a plurality of coaxial pairs of like coaxial elements rotating on horizontal transversely extending axes, planet means cooperating with the elements of each pair, means for rotating said coaxial elements including three worms rotating on axes lying in the same transverse plane, the central worm driving an element of each pair, and separate feed operating members each adapted to cooperate directly with flexible feeding means and each driven and controlled through one of said pairs of coaxial elements.
86. In a mining machine, feeding mechanism including a plurality of coaxial pairs of like coaxial elements rotating on horizontal transversely extending axes, planet means cooperating with the elements of each pair, means for rotating said coaxial elements including a plurality of worms one of which drives an element of each pair, and means to effect rotation of said worms including means for rotating each of said worms at will or holding it against rotation, and separate feed operating members each adapted to cooperate directly with flexible feeding means and each driven and controlled through one of said pairs of coaxial elements.
87. In a mining machine, feeding mechanism including a plurality of coaxial pairs of like coaxial elements rotating on horizontal transversely extending axes, planet means cooperating with the elements of each pair, means for rotating said coaxial elements including a plurality of worms rotating on parallel axes, one of which drives an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.
88. In a mining machine, feeding mechanism including a plurality of coaxial pairs of like coaxial elements rotating on horizontal transversely extending axes, planet means cooperating with the elements of each pair, means for rotating said coaxial elements including a plurality of worms rotating on horizontal axes, one of which drives an element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

ing members each adapted to cooperate directly with flexible feeding means and each driven and controlled through one of said pairs of coaxial elements.

5 89. In a mining machine, feeding mechanism including a plurality of coaxial pairs of like coaxial elements rotating on horizontal transversely extending axes, planet means cooperating with the elements of each pair, 10 means for rotating said coaxial elements including a plurality of worms rotating on axes lying in parallel planes extending longitudinally of the machine, one of which drives an element of each pair, means to effect 15 rotation of said worms including means for rotating each of said worms at will or holding it against rotation, and separate feed operating members each adapted to cooperate directly with flexible feeding means 20 and each driven and controlled through one of said pairs of coaxial elements.

90. In a mining machine, feeding mechanism including a plurality of coaxial pairs of like coaxial elements rotating on horizontal transversely extending axes, planet means 25 cooperating with the elements of each pair, means for rotating said coaxial elements including a plurality of worms rotating on axes lying in the same transverse plane, one 30 of which drives an element of each pair, means to effect rotation of said worms including means for rotating each of said worms at will or holding it against rotation, and separate feed operating members each 35 adapted to cooperate directly with flexible feeding means and each driven and controlled through one of said pairs of coaxial elements.

91. In a mining machine, feeding mechanism 40 including a plurality of coaxial pairs of like coaxial elements rotating on horizontal transversely extending axes, planet means cooperating with the elements of each pair, means for rotating said coaxial elements including three worms, the central worm driving 45 an element of each pair, means to effect rotation of said worms including means for rotating each of said worms at will or holding it against rotation, and separate feed operating members each adapted to cooperate 50 directly with flexible feeding means and each driven and controlled through one of said pairs of coaxial elements.

92. In a mining machine, feeding mechanism 55 including a plurality of coaxial pairs of like coaxial elements rotating on horizontal transversely extending axes, planet means cooperating with the elements of each pair, means for rotating said coaxial elements including three worms rotating on parallel 60 axes, the central worm driving an element of each pair, means to effect rotation of said worms including means for rotating each of said worms at will or holding it against rotation, and separate feed operating members 65

each adapted to cooperate directly with flexible feeding means and each driven and controlled through one of said pairs of coaxial elements.

93. In a mining machine, feeding mechanism 70 including a plurality of coaxial pairs of like coaxial elements rotating on horizontal transversely extending axes, planet means cooperating with the elements of each pair, means for rotating said coaxial elements including three worms rotating on horizontal axes, the central worm driving an element of each pair, means to effect rotation of said worms including means for rotating each of 75 said worms at will or holding it against rotation, and separate feed operating members each adapted to cooperate directly with flexible feeding means and each driven and controlled through one of said pairs of coaxial elements.

94. In a mining machine, feeding mechanism 80 including a plurality of coaxial pairs of like coaxial elements rotating on horizontal transversely extending axes, planet means cooperating with the elements of each pair, means for rotating said coaxial elements including three worms rotating on axes lying in parallel planes extending longitudinally of the machine, the central worm driving an 85 element of each pair, means to effect rotation of said worms including means for rotating each of said worms at will or holding it against rotation, and separate feed operating members each adapted to cooperate directly with flexible feeding means and each driven and controlled through one of said pairs of coaxial elements.

95. In a mining machine, feeding mechanism 90 including a plurality of coaxial pairs of like coaxial elements rotating on horizontal transversely extending axes, planet means cooperating with the elements of each pair, means for rotating said coaxial elements including three worms rotating on axes lying in the same transverse plane, the central worm driving an element of each pair, and separate feed operating members each adapted to cooperate directly with flexible feeding means and each driven and controlled 95 through one of said pairs of coaxial elements.

96. In a mining machine, feeding mechanism 100 including a plurality of coaxial pairs of like coaxial elements rotating on horizontal transversely extending axes, planet means cooperating with the elements of each pair, and means for rotating said coaxial elements including a plurality of worms one of which drives an element of each pair, and means for rotating each of said worms at will including means for rotating one of said worms at a plurality of speeds and means for holding each of said worms stationary.

97. In a mining machine, feeding mechanism 105 including a plurality of coaxial pairs

- means for rotating each of said worms at will including means for rotating said central worm at a plurality of speeds and means for holding each of said worms stationary.
- 5 107. In a mining machine, feeding mechanism including a plurality of coaxial pairs of like coaxial elements rotating on horizontal transversely extending axes, planet means cooperating with the elements of each pair, and means for rotating said coaxial elements including three worms rotating on parallel axes, the central worm driving an element of each pair, and means for rotating each of said worms at will including 10 means for rotating said central worm at a plurality of speeds and means for holding each of said worms stationary.
108. In a mining machine, feeding mechanism including a plurality of coaxial pairs 20 of like coaxial elements rotating on horizontal transversely extending axes, planet means cooperating with the elements of each pair, and means for rotating said coaxial elements including three worms rotating on horizontal axes, the central worm driving an element of each pair, and means for rotating each of said worms at will including 25 means for rotating said central worm at a plurality of speeds and means for holding each of said worms stationary.
109. In a mining machine, feeding mechanism including a plurality of coaxial pairs 30 of like coaxial elements rotating on horizontal transversely extending axes, planet means cooperating with the elements of each pair, and means for rotating said coaxial elements including three worms rotating on axes lying in parallel planes extending longitudinally of the machine, the central 35 worm driving an element of each pair, and means for rotating each of said worms at will including means for rotating said central worm at a plurality of speeds and means for holding each of said worms stationary.
- 40 110. In a mining machine, feeding mechanism including a plurality of coaxial pairs of like coaxial elements rotating on horizontal transversely extending axes, planet means cooperating with the elements of each pair, and means for rotating said coaxial elements including three worms rotating on axes lying in the same transverse plane, the central worm driving an element of each 45 pair, and means for rotating each of said worms at will including means for rotating said central worm at a plurality of speeds and means for holding each of said worms stationary.
- 50 111. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including a plurality of worms rotating on parallel axes, one of which drives an element of each pair.
- 55 112. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including a plurality of worms rotating on parallel axes, one of which drives an element of each pair.
- 60 113. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including a plurality of worms rotating on parallel axes, one of which drives an element of each pair.
- 65 114. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including a plurality of worms rotating on parallel axes, one of which drives an element of each pair.
- 70 115. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including a plurality of worms rotating on parallel axes, one of which drives an element of each pair.
- 75 116. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including a plurality of worms, the central worm driving an element of each pair.

117. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including three worms 70 rotating on parallel axes, the central worm 10 rotating on parallel axes, the central worm driving an element of each pair.

118. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating 80 said coaxial elements including three worms 15 rotating on horizontal axes, the central worm driving an element of each pair.

119. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating 90 20 said coaxial elements including three worms 25 rotating on axes lying in parallel planes extending longitudinally of the machine, the central worm driving an element of each 30 pair.

120. In a mining machine, feeding mechanism including a plurality of feed operating and controlling winding members, a plurality of pairs of like coaxial elements coaxial 95 35 with said feed operating members and rotating on horizontal transversely extending axes, planet means cooperating with the elements of each pair, and means for rotating said coaxial elements including three worms 40 45 rotating on axes lying in the same transverse plane, the central worm driving an element of each pair.

121. In a mining machine, feeding mechanism including a plurality of feed operating and controlling winding members, a plurality of pairs of like coaxial elements coaxial with said feed operating members and rotating on horizontal transversely extending axes, planet means cooperating with the 110 50 elements of each pair, and means for rotating said coaxial elements including a plurality of worms one of which drives an element of each pair, and means to effect rotation of said worms including means for rotating each of said worms at will or holding it against rotation.

122. In a mining machine, feeding mechanism including a plurality of feed operating and controlling winding members, a plurality of pairs of like coaxial elements coaxial 115 55

with said feed operating members and rotating on horizontal transversely extending axes, planet means cooperating with the elements of each pair, and means for rotating said coaxial elements including a plurality 75 of worms rotating on parallel axes, one of which drives an element of each pair, and means to effect rotation of said worms including means for rotating each of said worms at will or holding it against rotation. 80

123. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating 85 said coaxial elements including a plurality of worms rotating on horizontal axes, one of which drives an element of each pair, and means to effect rotation of said worms including means for rotating each of said worms at will or holding it against rotation. 90

124. In a mining machine, feeding mechanism including a plurality of feed operating and controlling winding members, a plurality of pairs of like coaxial elements coaxial with said feed operating members and rotating on horizontal transversely extending 95 axes, planet means cooperating with the elements of each pair, and means for rotating said coaxial elements including a plurality of worms rotating on axes lying in parallel planes extending longitudinally of the machine, one of which drives an element of each pair, and means to effect rotation of said worms including means for rotating each of said worms at will or holding it against rotation. 100

125. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including a plurality of worms rotating on axes lying in the same transverse plane, one of which drives an element of each pair, and means to effect rotation of said worms including means for rotating each of said worms at will or holding it against rotation. 110

126. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including three worms, the central worm driving an element of each 125 130

pair, and means to effect rotation of said worms including means for rotating each of said worms at will or holding it against rotation.

127. In a mining machine, feeding mechanism including a plurality of feed operating and controlling winding members, a plurality of pairs of like coaxial elements coaxial with said feed operating members and 10 rotating on horizontal transversely extending axes, planet means cooperating with the elements of each pair, and means for rotating said coaxial elements including three worms rotating on parallel axes, the central 16 worm driving an element of each pair, and means to effect rotation of said worms including means for rotating each of said worms at will or holding it against rotation.

128. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including three worms rotating on horizontal axes, the central worm driving an element of each 25 pair, and means to effect rotation of said worms including means for rotating each of said worms at will or holding it against rotation.

129. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including three worms rotating on axes lying in parallel planes extending longitudinally of the machine, the central worm driving an element of each pair, and means to effect rotation of said worms including means for rotating each of said worms at will or holding it against rotation.

130. In a mining machine, feeding mechanism including a plurality of feed operating and controlling winding members, a plurality of pairs of like coaxial elements coaxial with said feed operating members and rotating on horizontal transversely extending axes, planet means cooperating with the elements of each pair, and means for rotating said coaxial elements including three worms rotating on axes lying in the same transverse plane, the central worm driving an element of each pair.

131. In a mining machine, feeding mechanism including a plurality of feed operating and controlling members, a plurality of pairs of like coaxial elements coaxial with

said feed operating members and rotating on horizontal transversely extending axes, planet means cooperating with the elements of each pair, and means for rotating said coaxial elements including a plurality of worms one of which drives an element of each pair, and means for rotating each of said worms at will including means for rotating one of said worms at a plurality of speeds and means for holding each of said worms stationary. 70

132. In a mining machine, feeding mechanism including a plurality of feed operating and controlling members, a plurality of pairs of like coaxial elements coaxial with 80 said feed operating members and rotating on horizontal transversely extending axes, planet means cooperating with the elements of each pair, and means for rotating said coaxial elements including a plurality of worms rotating on parallel axes, one of which drives an element of each pair, and means for rotating each of said worms at will including means for rotating one of said worms at a plurality of speeds and means 90 for holding each of said worms stationary.

133. In a mining machine, feeding mechanism including a plurality of feed operating and controlling members, a plurality of pairs of like coaxial elements coaxial with said feed operating members and rotating on horizontal transversely extending axes, planet means cooperating with the elements of each pair, and means for rotating said coaxial elements including a plurality of worms rotating on horizontal axes, one of which drives an element of each pair, and means for rotating each of said worms at will including means for rotating one of said worms at a plurality of speeds and means 100 for holding each of said worms stationary. 95

134. In a mining machine, feeding mechanism including a plurality of feed operating and controlling members, a plurality of pairs of like coaxial elements coaxial with said feed operating members and rotating on horizontal transversely extending axes, planet means cooperating with the elements of each pair, and means for rotating said coaxial elements including a plurality of worms rotating on axes lying in parallel planes extending longitudinally of the machine, one of which drives an element of each pair, and means for rotating each of said worms at will including means for rotating one of said worms at a plurality of speeds and means for holding each of said worms stationary. 110

135. In a mining machine, feeding mechanism including a plurality of feed operating and controlling members, a plurality of pairs of like coaxial elements coaxial with said feed operating members and rotating on horizontal transversely extending axes, planet means cooperating with the ele- 125 130

cluding means for rotating said central worm at a plurality of speeds and means for holding each of said worms stationary.

144. In a mining machine, feeding mechanism including a plurality of feed operating and controlling members, a plurality of pairs of like coaxial elements coaxial with said feed operating members and rotating on horizontal transversely extending axes, 5 planet means cooperating with the elements of each pair, and means for rotating said coaxial elements including three worms rotating on axes lying in parallel planes extending longitudinally of the machine, the 10 central worm driving an element of each pair, and means for rotating each of said worms at will including means for rotating said central worm at a plurality of speeds and means for holding each of said worms 15 stationary.

145. In a mining machine, feeding mechanism including a plurality of feed operating and controlling members, a plurality of pairs of like coaxial elements coaxial with 25 said feed operating members and rotating on horizontal transversely extending axes, planet means cooperating with the elements of each pair, and means for rotating said coaxial elements including three worms 30 rotating on axes lying in the same transverse plane, the central worm driving an element of each pair, and means for rotating each of said worms at will including means for rotating said central worm at a plurality of 35 speeds and means for holding each of said worms stationary.

146. In a mining machine, feeding mechanism including a plurality of pairs of like coaxial elements rotating on horizontal 40 transversely extending axes, planet means cooperating with the elements of each pair, means for rotating said coaxial elements including a plurality of worms one of which drives an element of each pair, and controlling 45 means for said worms including clutches one coaxial with each of the same, and separate feed operating members each adapted to cooperate directly with flexible feeding means and each driven and controlled through one of said pairs of coaxial 50 elements.

147. In a mining machine, feeding mechanism including a plurality of pairs of like coaxial elements rotating on horizontal 55 transversely extending axes, planet means cooperating with the elements of each pair, means for rotating said coaxial elements including a plurality of worms rotating on parallel axes, one of which drives an element of each pair, and controlling means for 60 said worms including clutches one coaxial with each of the same, and separate feed operating members each adapted to cooperate directly with flexible feeding means and

each driven and controlled through one of 65 said pairs of coaxial elements.

148. In a mining machine, feeding mechanism including a plurality of pairs of like coaxial elements rotating on horizontal 70 transversely extending axes, planet means 75 cooperating with the elements of each pair, means for rotating said coaxial elements including a plurality of worms rotating on horizontal axes, one of which drives an element of each pair, and controlling means for 80 said worms including clutches one coaxial with each of the same, and separate feed operating members each adapted to cooperate directly with flexible feeding means and each driven and controlled through one of 85 said pairs of coaxial elements.

149. In a mining machine, feeding mechanism including a plurality of pairs of like coaxial elements rotating on horizontal 90 transversely extending axes, planet means 95 cooperating with the elements of each pair, means for rotating said coaxial elements including a plurality of worms rotating on axes lying in parallel planes extending longitudinally of the machine, one of which drives an element of each pair, controlling means for said worms including clutches one coaxial with each of the same, and separate feed operating members each adapted to 100 cooperate directly with flexible feeding means 95 and each driven and controlled through one of said pairs of coaxial elements.

150. In a mining machine, feeding mechanism including a plurality of pairs of like coaxial elements rotating on horizontal 105 transversely extending axes, planet means 110 cooperating with the elements of each pair, means for rotating said coaxial elements including a plurality of worms rotating on axes lying in the same transverse plane, one 115 of which drives an element of each pair, controlling means for said worms including clutches one coaxial with each of the same, and separate feed operating members each 120 adapted to cooperate directly with flexible feeding means and each driven and controlled through one of said pairs of coaxial elements.

151. In a mining machine, feeding mechanism including a plurality of pairs of like 115 coaxial elements rotating on horizontal transversely extending axes, planet means 120 cooperating with the elements of each pair, means for rotating said coaxial elements including three worms, the central worm driving an element of each pair, controlling means for said worms including clutches one coaxial with each of the same, and separate feed operating members each adapted to 125 cooperate directly with flexible feeding means and each driven and controlled through one of said pairs of coaxial elements.

152. In a mining machine, feeding mecha-

- nism including a plurality of pairs of like coaxial elements rotating on horizontal transversely extending axes, planet means cooperating with the elements of each pair, 65
- 5 means for rotating said coaxial elements including three worms rotating on parallel axes, the central worm driving an element of each pair, controlling means for said worms including clutches one coaxial with each of 75
- 10 the same, and separate feed operating members each adapted to cooperate directly with flexible feeding means and each driven and controlled through one of said pairs of coaxial elements. 80
- 15 153. In a mining machine, feeding mechanism including a plurality of pairs of like coaxial elements rotating on horizontal transversely extending axes, planet means cooperating with the elements of each pair, 85
- 20 means for rotating said coaxial elements including three worms rotating on horizontal axes, the central worm driving an element of each pair, controlling means for said worms including clutches one coaxial with each of 90
- 25 the same, and separate feed operating members each adapted to cooperate directly with flexible feeding means and each driven and controlled through one of said pairs of coaxial elements. 95
- 30 154. In a mining machine, feeding mechanism including a plurality of pairs of like coaxial elements rotating on horizontal transversely extending axes, planet means cooperating with the elements of each pair, 100
- 35 means for rotating said coaxial elements including three worms rotating on axes lying in parallel planes extending longitudinally of the machine, the central worm driving an element of each pair, controlling means for 105
- 40 said worms including clutches one coaxial with each of the same, and separate feed operating members each adapted to cooperate directly with flexible feeding means and each driven and controlled through one of 110
- 45 said pairs of coaxial elements. 115
155. In a mining machine, feeding mechanism including a plurality of pairs of like coaxial elements rotating on horizontal transversely extending axes, planet means 120
- 50 cooperating with the elements of each pair, means for rotating said coaxial elements including three worms rotating on axes lying in the same transverse plane, the central worm driving an element of each pair, con- 125
- 55 trolling means for said worms including clutches one coaxial with each of the same, and separate feed operating members each adapted to cooperate directly with flexible feeding means and each driven and controlled through one of said pairs of coaxial elements.
- 60 156. In a mining machine, feeding mechanism including a plurality of pairs of like coaxial elements rotating on horizontal
- transversely extending axes, planet means cooperating with the elements of each pair, including a plurality of worms one of which drives an element of each pair, means to effect rotation of said worms including means for rotating each of said worms at will or holding it against rotation, the means for controlling rotation of said worms including a driving clutch and a braking clutch coaxial with each of said worms, and separate feed operating members each adapted to cooperate directly with flexible feeding means and each driven and controlled through one of said pairs of coaxial elements. 80
157. In a mining machine, feeding mechanism including a plurality of pairs of like coaxial elements rotating on horizontal transversely extending axes, planet means cooperating with the elements of each pair, 85
- means for rotating said coaxial elements including a plurality of worms rotating on parallel axes, one of which drives an element of each pair, and means to effect rotation of said worms including means for rotating each of said worms at will or holding it against rotation, the means for controlling rotation of said worms including a driving clutch and a braking clutch coaxial with each of said worms, and separate feed operating members each adapted to cooperate directly with flexible feeding means and each driven and controlled through one of said pairs of coaxial elements. 90
158. In a mining machine, feeding mechanism including a plurality of pairs of like coaxial elements rotating on horizontal transversely extending axes, planet means cooperating with the elements of each pair, 100
- means for rotating said coaxial elements including a plurality of worms rotating on horizontal axes, one of which drives an element of each pair, means to effect rotation of said worms including means for rotating each of said worms at will or holding it against rotation, the means for controlling rotation of said worms including a driving clutch and a braking clutch coaxial with each of said worms, and separate feed operating members each adapted to cooperate directly with flexible feeding means and each driven and controlled through one of said pairs of coaxial elements. 105
159. In a mining machine, feeding mechanism including a plurality of pairs of like coaxial elements rotating on horizontal transversely extending axes, planet means cooperating with the elements of each pair, 110
- means for rotating said coaxial elements including a plurality of worms rotating on axes lying in parallel planes extending longitudinally of the machine, one of which drives an element of each pair, means to ef- 115

fect rotation of said worms including means for rotating each of said worms at will or holding it against rotation, the means for controlling rotation of said worms including 5 a driving clutch and a braking clutch coaxial with each of said worms, and separate feed operating members each adapted to cooperate directly with flexible feeding means and each driven and controlled through one of 10 said pairs of coaxial elements.

160. In a mining machine, feeding mechanism including a plurality of pairs of like coaxial elements rotating on horizontal transversely extending axes, planet means 15 cooperating with the elements of each pair, means for rotating said coaxial elements including a plurality of worms rotating on axes lying in the same transverse plane, one of which drives an element of each pair, and 20 means to effect rotation of said worms including means for rotating each of said worms at will or holding it against rotation, the means for controlling rotation of said worms including a driving clutch and a 25 braking clutch coaxial with each of said worms, and separate feed operating members each adapted to cooperate directly with flexible feeding means and each driven and controlled through one of said pairs of coaxial 30 elements.

161. In a mining machine, feeding mechanism including a plurality of pairs of like coaxial elements rotating on horizontal transversely extending axes, planet means 35 cooperating with the elements of each pair, means for rotating said coaxial elements including three worms, the central worm driving an element of each pair, means to effect rotation of said worms including means for 40 rotating each of said worms at will or holding it against rotation, the means for controlling rotation of said worms including a driving clutch and a braking clutch coaxial with each of said worms, and separate feed 45 operating members each adapted to cooperate directly with flexible feeding means and each driven and controlled through one of said pairs of coaxial elements.

162. In a mining machine, feeding mechanism including a plurality of pairs of like coaxial elements rotating on horizontal transversely extending axes, planet means 50 cooperating with the elements of each pair, means for rotating said coaxial elements including three worms rotating on parallel axes, the central worm driving an element of each pair, means to effect rotation of said worms including means for rotating each of 55 said worms at will or holding it against rotation, the means for controlling rotation of said worms including a driving clutch and a braking clutch coaxial with each of said worms, and separate feed 60 operating members each adapted to cooperate directly with flexible feeding means and each driven and controlled 65 through one of said pairs of coaxial elements.

controlled through one of said pairs of coaxial elements.

163. In a mining machine, feeding mechanism including a plurality of pairs of like coaxial elements rotating on horizontal 70 transversely extending axes, planet means cooperating with the elements of each pair, means for rotating said coaxial elements including three worms rotating on horizontal axes, the central worm driving an element 75 of each pair, means to effect rotation of said worms including means for rotating each of said worms at will or holding it against rotation, the means for controlling rotation of 80 said worms including a driving clutch and a braking clutch coaxial with each of said worms, and separate feed operating members each adapted to cooperate directly with flexible feeding means and each driven and controlled through one of said pairs of coaxial 85 elements.

164. In a mining machine, feeding mechanism including a plurality of pairs of like coaxial elements rotating on horizontal transversely extending axes, planet means 90 cooperating with the elements of each pair, means for rotating said coaxial elements including three worms rotating on axes lying in parallel planes extending longitudinally of the machine, the central worm driving 95 an element of each pair, means to effect rotation of said worms including means for rotating each of said worms at will or holding it against rotation, the means for controlling rotation of said worms including a 100 driving clutch and a braking clutch coaxial with each of said worms, and separate feed operating members each adapted to cooperate directly with flexible feeding means and each driven and controlled through one of 105 said pairs of coaxial elements.

165. In a mining machine, feeding mechanism including a plurality of pairs of like coaxial elements rotating on horizontal transversely extending axes, planet means 110 cooperating with the elements of each pair, means for rotating said coaxial elements including three worms rotating on axes lying in the same transverse plane, the central worm driving an element of each pair, means 115 to effect rotation of said worms including means for rotating each of said worms at will or holding it against rotation, the means for controlling rotation of said worms including a driving clutch and a braking clutch coaxial with each of said worms, and separate feed 120 operating members each adapted to cooperate directly with flexible feeding means and each driven and controlled 125 through one of said pairs of coaxial elements.

166. In a mining machine, feeding mechanism including a plurality of pairs of like coaxial elements rotating on horizontal transversely extending axes, planet means 130

cooperating with the elements of each pair, and means for rotating said coaxial elements including a plurality of worms one of which drives an element of each pair, and means for rotating each of said worms at will including means for rotating one of said worms at a plurality of speeds and means for holding each of said worms stationary, the means for controlling rotation of said worms including a driving clutch and a braking clutch coaxial with each of said worms.

167. In a mining machine, feeding mechanism including a plurality of pairs of like coaxial elements rotating on horizontal transversely extending axes, planet means 15 cooperating with the elements of each pair, and means for rotating said coaxial elements including a plurality of worms rotating on parallel axes, one of which drives an element 20 of each pair, and means for rotating each of said worms at will including means for rotating one of said worms at a plurality of speeds and means for holding each of said 25 worms stationary, the means for controlling rotation of said worms including a driving clutch and a braking clutch coaxial with each of said worms.

168. In a mining machine, feeding mechanism including a plurality of pairs of like coaxial elements rotating on horizontal transversely extending axes, planet means cooperating with the elements of each pair, and means for rotating said coaxial elements including a plurality of worms rotating on horizontal axes, one of which drives an element of each pair, and means for rotating each of said worms at will including means for rotating one of said worms at a plurality of speeds and means for holding each of said worms stationary, the means for controlling rotation of said worms including a driving clutch and a braking clutch coaxial with each of said worms.

45 169. In a mining machine, feeding mechanism including a plurality of pairs of like coaxial elements rotating on horizontal transversely extending axes, planet means 50 cooperating with the elements of each pair, and means for rotating said coaxial elements including a plurality of worms rotating on axes lying in parallel planes extending longitudinally of the machine, one of which drives an element of each pair, and means 55 for rotating each of said worms at will including means for rotating one of said worms at a plurality of speeds and means for holding each of said worms stationary, the means for controlling rotation of said 60 worms including a driving clutch and a braking clutch coaxial with each of said worms.

170. In a mining machine, feeding mechanism including a plurality of pairs of like coaxial elements rotating on horizontal

transversely extending axes, planet means cooperating with the elements of each pair, and means for rotating said coaxial elements including a plurality of worms rotating on axes lying in the same transverse plane; one of which drives an element of each pair, and means for rotating each of said worms at will including means for rotating one of said worms at a plurality of speeds and means for holding each of said worms stationary, the means for controlling rotation of said worms including a driving clutch and a braking clutch coaxial with each of said worms. 70 75

171. In a mining machine, feeding mechanism including a plurality of pairs of like coaxial elements rotating on horizontal transversely extending axes, planet means cooperating with the elements of each pair, and means for rotating said coaxial elements including three worms, the central worm driving an element of each pair, and means for rotating each of said worms at will including means for rotating one of said worms at a plurality of speeds and means for holding each of said worms stationary, the means for controlling rotation of said worms including a driving clutch and a braking clutch coaxial with each of said worms. 80 85 90 95

172. In a mining machine, feeding mechanism including a plurality of pairs of like coaxial elements rotating on horizontal transversely extending axes, planet means 100 cooperating with the elements of each pair, and means for rotating said coaxial elements including three worms rotating on parallel axes, the central worm driving an element of each pair, and means for rotating each of said worms at will including means for rotating one of said worms at a plurality of speeds and means for holding each of said worms stationary, the means for controlling rotation of said worms including a driving clutch and a braking clutch coaxial with each of said worms. 105 110

173. In a mining machine, feeding mechanism including a plurality of pairs of like coaxial elements rotating on horizontal transversely extending axes, planet means cooperating with the elements of each pair, and means for rotating said coaxial elements including three worms rotating on horizontal axes, the central worm driving an element of each pair, and means for rotating each of said worms at will including means for rotating one of said worms at a plurality of speeds and means for holding each of said worms stationary, the means for controlling rotation of said worms including a driving clutch and a braking clutch coaxial with each of said worms.

174. In a mining machine, feeding mechanism including a plurality of pairs of like coaxial elements rotating on horizontal 180

transversely extending axes, planet means cooperating with the elements of each pair, and means for rotating said coaxial elements including three worms rotating on axes lying in parallel planes extending longitudinally of the machine, the central worm driving an element of each pair, and means for rotating each of said worms at will including means for rotating one of said worms at a plurality of speeds and means for holding each of said worms stationary, the means for controlling rotation of said worms including a driving clutch and a braking clutch coaxial with each of said worms.

175. In a mining machine, feeding mechanism including a plurality of pairs of like coaxial elements rotating on horizontal transversely extending axes, planet means cooperating with the elements of each pair, and means for rotating said coaxial elements including three worms rotating on axes lying in the same transverse plane, the central worm driving an element of each pair, and means for rotating each of said worms at will including means for rotating one of said worms at a plurality of speeds and means for holding each of said worms stationary, the means for controlling rotation of said worms including a driving clutch and a braking clutch coaxial with each of said worms.

176. In a mining machine, feeding mechanism including a plurality of pairs of like coaxial elements rotating on horizontal transversely extending axes, planet means cooperating with the elements of each pair, and means for rotating said coaxial elements including three worms, the central worm driving an element of each pair, and means for rotating each of said worms at will including means for rotating said central worm at a plurality of speeds and means for holding each of said worms stationary, the means for controlling rotation of said worms including a driving clutch and a braking clutch coaxial with each of said worms.

177. In a mining machine, feeding mechanism including a plurality of pairs of like coaxial elements rotating on horizontal transversely extending axes, planet means cooperating with the elements of each pair, and means for rotating said coaxial elements including three worms rotating on parallel axes, the central worm driving an element of each pair, and means for rotating each of said worms at will including means for rotating said central worm at a plurality of speeds and means for holding each of said worms stationary, the means for controlling rotation of said worms including a driving clutch and a braking clutch coaxial with each of said worms.

178. In a mining machine, feeding mechanism including a plurality of pairs of like coaxial elements rotating on horizontal

transversely extending axes, planet means cooperating with the elements of each pair, and means for rotating said coaxial elements including three worms rotating on horizontal axes, the central worm driving an element of each pair, and means for rotating each of said worms at will including means for rotating said central worm at a plurality of speeds and means for holding each of said worms stationary, the means for controlling rotation of said worms including a driving clutch and a braking clutch coaxial with each of said worms.

179. In a mining machine, feeding mechanism including a plurality of pairs of like coaxial elements rotating on horizontal transversely extending axes, planet means cooperating with the elements of each pair, and means for rotating said coaxial elements including three worms rotating on axes lying in parallel planes extending longitudinally of the machine, the central worm driving an element of each pair, and means for rotating each of said worms at will including means for rotating said central worm at a plurality of speeds and means for holding each of said worms stationary, the means for controlling rotation of said worms including a driving clutch and a braking clutch coaxial with each of said worms.

180. In a mining machine, feeding mechanism including a plurality of pairs of like coaxial elements rotating on horizontal transversely extending axes, planet means cooperating with the elements of each pair, and means for rotating said coaxial elements including three worms rotating on axes lying in the same transverse plane, the central worm driving an element of each pair, and means for rotating each of said worms at will including means for rotating said central worm at a plurality of speeds and means for holding each of said worms stationary, the means for controlling rotation of said worms including a driving clutch and a braking clutch coaxial with each of said worms.

181. In a mining machine, a feed operating member adapted to cooperate with a flexible feeding member, a motor, and means for transmitting power from said motor to said member including a worm, and a friction clutch coaxial with said worm and more remote from said motor than said worm.

182. In a mining machine, a motor, a feed operating member rotatable on an axis lying in a transversely extending vertical plane and adapted to cooperate directly with a flexible feeding member, and means for transmitting power from said motor to said member including a plurality of coaxial members, two of which support coaxial gear members and another of which supports planet means meshing with said gear mem-

bers, means for effecting rotation of two of said members by power from said motor through power connections not including the third, and means connecting the other of said members in driving relation to said feed operating member.

183. In a mining machine, a motor, a feed operating member rotatable on an axis lying in a transversely extending vertical plane and adapted to cooperate directly with a flexible feeding member, and means for transmitting power from said motor to said member including a plurality of coaxial members, two of which support coaxial gear members and another of which supports planet means meshing with said gear members, means for effecting rotation of two of said members at different speeds by power from said motor through power connections not including the third, and means connecting the other of said members in driving relation to said feed operating member.

184. In a mining machine, a motor, a feed operating member rotatable on an axis lying in a transversely extending vertical plane and adapted to cooperate directly with a flexible feeding member, and means for transmitting power from said motor to said member including a plurality of coaxial members, two of which support coaxial gear members and another of which supports planet means meshing with said gear members, means for effecting rotation of two of said members simultaneously in opposite directions by power from said motor, and means connecting the other of said members in driving relation to said feed operating member.

185. In a mining machine, a motor, a feed operating member rotatable on an axis lying in a transversely extending vertical plane and adapted to cooperate directly with a flexible feeding member, and means for transmitting power from said motor to said member including a plurality of coaxial members, two of which support coaxial gear members and another of which supports planet means meshing with said gear members, means for effecting rotation of two of said members simultaneously in opposite directions at different speeds by power from said motor, and means connecting the other of said members in driving relation to said feed operating member.

186. In a mining machine, a motor, a feed operating member rotatable on an axis lying in a transversely extending vertical plane and adapted to cooperate directly with a flexible feeding member, and means for transmitting power from said motor to said member including a plurality of coaxial members, two of which support coaxial gear members and another of which supports planet means meshing with said gear mem-

bers, means for effecting rotation of two of said members separately or together by power from said motor through power connections not including the third, and means connecting the other of said members in driving relation to said feed operating member.

187. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms operatively connected to said coaxial elements respectively and constituting driving means therefor, and means for effecting rotation of said member on orbital movement of said planet means.

188. In a mining machine, a motor and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, horizontal worms operatively connected to said coaxial elements and constituting driving means therefor, and means for effecting rotation of said member on orbital movement of said planet means.

189. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms rotating on axes in longitudinally extending vertical planes operatively connected to said coaxial elements respectively and constituting driving means therefor, and means for effecting rotation of said member on orbital movement of said planet means.

190. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, worms rotating on axes lying in the same transversely extending plane operatively connected to said coaxial elements respectively and constituting driving means therefor,

- and means for effecting rotation of said member on orbital movement of said planet means.
191. In a mining machine, a motor, and feeding mechanism operated by said motor including a flexible feeding portion, a rotatable feed operating and controlling member cooperating directly therewith, and operating and controlling means for said member including coaxial elements rotating on transversely extending horizontal axes, planet means cooperating with said elements, horizontal worms rotating on axes lying in the same transversely extending plane operatively connected to said coaxial elements and constituting driving means therefor, and means for effecting rotation of said member on orbital movement of said planets. 65
192. In a mining machine, a motor, and feeding mechanism operated by said motor including a flexible feeding portion, a rotatable feed operating and controlling member cooperating directly therewith, and operating and controlling means for said member including like coaxial elements rotating on transversely extending horizontal axes, planet means cooperating with said elements, worms operatively connected to said coaxial elements respectively and constituting driving means therefor, and means for effecting rotation of said member on orbital movement of said planet means. 70
193. In a mining machine, a motor, and feeding mechanism operated by said motor including a flexible feeding portion, a rotatable feed operating and controlling member cooperating directly therewith, and operating and controlling means for said member including like coaxial elements rotating on transversely extending horizontal axes, planet means cooperating with said elements, horizontal worms operatively connected to said coaxial elements and constituting driving means therefor, and means for effecting rotation of said member on orbital movement of said planets. 75
194. In a mining machine, a motor, and feeding mechanism operated by said motor including a flexible feeding portion, a rotatable feed operating and controlling member cooperating directly therewith, and operating and controlling means for said member including like coaxial elements rotating on transversely extending horizontal axes, planet means cooperating with said elements, worms rotating on axes in longitudinally extending vertical planes operatively connected to said coaxial elements respectively and constituting driving means therefor, and means for effecting rotation of said member on orbital movement of said planet means. 80
195. In a mining machine, a motor, and feeding mechanism operated by said motor including a flexible feeding portion, a rotatable feed operating and controlling member cooperating directly therewith, and operating and controlling means for said member including like coaxial elements rotating on transversely extending horizontal axes, planet means cooperating with said elements, worms rotating on axes lying in the same transversely extending plane operatively connected to said coaxial elements respectively and constituting driving means therefor, and means for effecting rotation of said member on orbital movement of said planet means. 85
196. In a mining machine, a motor, and feeding mechanism operated by said motor including a flexible feeding portion, a rotatable feed operating and controlling member cooperating directly therewith, and operating and controlling means for said member including like coaxial elements rotating on transversely extending horizontal axes, planet means cooperating with said elements, horizontal worms rotating on axes lying in the same transversely extending plane operatively connected to said coaxial elements and constituting driving means therefor, and means for effecting rotation of said member on orbital movement of said planets. 90
197. In a mining machine, a feed operating member adapted to cooperate with a flexible feeding member, a motor, and means for transmitting power from said motor to said member including a worm rotating on a horizontal axis, and a friction clutch coaxial with said worm and more remote from said motor than said worm. 95
198. In a mining machine, a motor, and feeding mechanism driven by said motor adapted to cooperate with flexible feeding means and including coaxial driving elements and a plurality of planet mechanisms operatively connected to said driving elements, each planet mechanism being operatively connected to two driving elements. 100
199. In a mining machine, a motor, and feeding mechanism driven by said motor including coaxial driving elements rotating on horizontal transversely extending axes, planet means cooperating with said elements, each planet means being operatively connected to two driving elements, and means for effecting rotation of one of said driving elements at different speeds. 105
200. In a mining machine, a motor, and feeding mechanism driven by said motor including coaxial driving elements rotating on horizontal transversely extending axes, planet means cooperating with said elements, and means for effecting rotation of the central driving element at different speeds. 110
201. In a mining machine, a motor, and feeding mechanism driven by said motor including coaxial driving elements rotating on

horizontal transversely extending axes, planet means cooperating with said elements, means for effecting rotation of the central driving element at different speeds, and 5 means for effecting rotation of the end driving elements at a constant speed in the same direction.

202. In a mining machine, a motor, and feeding mechanism driven by said motor 10 adapted to cooperate with flexible feeding

means and including coaxial driving elements and a plurality of planet mechanisms operatively connected to said driving elements, each planet mechanism being operatively connected to two driving elements, 15 and means for effecting rotation of one of said driving elements at different speeds.

In testimony whereof I affix my signature.

CHARLES F. OSGOOD.

CERTIFICATE OF CORRECTION.

Patent No. 1,662,796.

Granted March 13, 1928, to

CHARLES F. OSGOOD.

It is hereby certified that error appears in the printed specification of the above numbered patent requiring correction as follows: Page 3, line 71 for the word "from" read "form"; pages 11 and 15, lines 87 and 111, claims 66 and 105, for the word "element" read "elements"; and that the said Letters Patent should be read with these corrections therein that the same may conform to the record of the case in the Patent Office.

Signed and sealed this 24th day of April, A. D. 1928.

(Seal)

M. J. Moore,
Acting Commissioner of Patents.
